CLAIM

The ornamental design for an electronic tablet, as shown and described.

DESCRIPTION

FIG. 1 is a front isometric view of an electronic tablet showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 6A is a top view of the electronic tablet of FIG. 6 showing a call-out region thereon;

FIG. 7 is an enlarged top view of the callout region in the electronic tablet as indicated in FIG. 6A; and,

FIG. 8 is a bottom view of the electronic tablet showing our new design.

The broken line showing of various features of the electronic tablet are for environmental purposes only and form no part of the claimed design.

1 Claim, 7 Drawing Sheets(56)
